GUIDE MECHANISM FOR METAL DRAWING PRESS

Einar K. Johansen, Oak Park, Ill., assignor, by mesne assignments, to U.S. Industries, Inc., a corporation of Delaware

Filed June 7, 1954, Ser. No. 434,854

3 Claims. (Cl. 113—38)

This invention relates in general to metal working presses and is particularly directed to a novel form of guide means for guiding the reciprocating movements of the slides in such presses whereby certain disadvantages inherent in such presses as they have been constructed heretofore are able to be overcome.

The invention is applicable to single action as well as to multiple action presses as will be more clearly pointed out hereinafter. Heretofore all types of such presses have been provided with gibs in the frame of the press which had to be machined accurately for guiding corresponding gibs or guide surfaces on the slide. The present novel form of guide means eliminates such gibs as well as the attendant expense involved in machining them.

As far as a single action press is concerned, a 4-point press can now be a 2-point press by using the present invention with all of the advantages of a 4-point press. Furthermore, the present invention provides for a greater span of the guides because they are longer than has been possible heretofore by the use of gibs with the result that the products produced by the press are more accurate.

In multiple action presses one great disadvantage has been that an adjustment of the blank holder for proper alignment would almost invariably cause the inner slide to become out of alignment because the inner slide was guided by the outer slide. This disadvantage is overcome because the present invention provides guide means for both slides independently. Still further, the present invention enables the blank holder to be adjusted by power with a fine hand adjustment without affecting the alignment of the inner slide.

In view of the foregoing, it is a principal object of the present invention to provide a novel form of guide means for metal working presses which is designed to overcome the disadvantages enumerated above which are present in the conventional structures of such presses.

Another object of the invention is to provide a form of guide means for the slides of metal working presses which is adaptable for use either with single action or with multiple action presses.

A further object is to provide a novel form of guide means for the reciprocating slides of metal working presses wherein there is present a greater guide span than has been possible heretofore whereby a more accurate product will result.

Still another object is to provide a novel form of guide means to guide the reciprocating movements of the slides in a metal working press wherein the alignment of the slides may be easily accomplished and wherein the alignment of one slide of a multiple action press may be corrected or adjusted without affecting the alignment of the other slide.

A still further object of the invention is to provide a guide means for guiding the reciprocating movements of the slide or slides in a single or multiple action metal

2

working press which are independent of each other and which include the provision of guide rods for each slide, thereby eliminating gibs which have been necessary heretofore.

Another object of the invention is to provide guide means which include guide rods movable with the slide or slides of a single or multiple action metal working press, wherein each guide rod is separately guided and wherein independent adjustments of the individual slides with respect to the guide rods may be accomplished.

Other objects and advantages of the invention will become apparent upon reading the following description taken in conjunction with the accompanying drawings, in which:

15 Fig. 1 is a side elevational view of a single action press embodying the present invention;

Fig. 2 is a vertical sectional view through the press of Fig. 1 taken along the plane of line 2—2 of Fig. 4;

Fig. 3 is an enlarged fragmentary sectional view of a detail illustrated in Fig. 2;

Fig. 4 is a view partly in front elevation and partly in section wherein the section is taken along the plane of line 4—4 of Fig. 4;

Fig. 5 is a perspective view of a double action press 25 embodying the present invention with parts thereof broken away and shown in section for the sake of clarity;

Fig. 6 is a double sectional view of the press shown in Fig. 5 wherein the left-hand half of the figure is a section taken along the plane of line 6—6 of Fig. 7 and wherein the right-hand half is a section taken along the plane of line 6a—6a of Fig. 7;

Fig. 7 is a view partly in front elevation and partly in section of a double action press wherein the section is taken along the plane of line 7—7 of Fig. 6;

35 Fig. 8 is a view partly in side elevation and partly in section of a triple action press embodying the present invention wherein the sectional portion is taken along the plane of line 8—8 of Fig. 10;

Fig. 9 is a vertical sectional view taken along the plane of line 9—9 of Fig. 8, and

Fig. 10 is a vertical sectional view taken along the plane of line 10—10 of Fig. 8.

As stated above, the invention relates primarily and specifically to a novel form of guide means for guiding the reciprocating movements of the slide or slides in a single action or multiple action metal working press. Figs. 1 to 4 inclusive of the drawings illustrate one form of single action press and it will be understood that the particular form of press illustrated is not intended to be limiting since the principle involved in the invention is applicable to any type of press wherein reciprocating slides must be guided in their movements.

The single action press shown in Figs. 1 to 4 inclusive is a typical bottom drive press having a pair of opposed uprights 1 and 2 connected at the top portions thereof by the connecting beam or cross member 3. A bed 4 is provided for the purpose of supporting a die thereon which is adapted to cooperate with a complementary die or punch on the draw slide.

60 A crosshead 5 is located at each side of the machine and is mounted upon guide rods 6 at the front of the press and similar guide rods 7 at the rear of the press. Each guide rod 6 has a portion 6a of smaller diameter at its lower end, thereby providing a shoulder 6b against which the upper part of the crosshead 5 may abut. A collar 8 mounted on the smaller portion 6a of guide rod 6 bears upwardly against the lower part of the crosshead 5, thereby to maintain the crosshead and guide rod in assembled relation.

65 The rear guide rods 7 are likewise formed with a portion 7a of smaller diameter forming a shoulder 7b and each has a collar 9 so that the crosshead 5 is held between

the shoulder 7b and collar 9. When the crosshead is caused to reciprocate as will be presently seen, the guide rods 6 and 7 will be carried therewith.

The slide is of the usual construction and is indicated by the numeral 10. In this case, however, the slide is not provided with any gibbs for cooperation with guiding gibbs on the frame, but rather is mounted on the guide rods 6 and 7. It will be noted from Figs. 2, 3 and 4 that the front and rear guide rods 6 and 7 are each provided with a threaded portion 11 and 12 respectively, for engagement with the slide 10. The means for adjustably mounting the slide on the guide rods for adjustment with respect thereto is well known and since there is one such mounting means for each rod, a description of one will suffice for all. Each guide rod has associated therewith a housing 13 mounted on the upper part of the slide 10 which has an inwardly extending flange 14 overlying a shoulder 15 formed in an internally threaded member 16 which is provided at its upper end with bevel gear teeth 17. The member 16 is thus free to rotate but since it is in threaded engagement with its associated guide rod 6 or 7, the rotation thereof will cause the slide to move with respect thereto.

A suitable drive mechanism of a well known construction is mounted on the upper part of the slide 10 and includes a bevel gear 18 mounted on a shaft 19 for each of the bevel gears 17. Thus, when the shaft 19 is rotated together with the bevel gear 18 thereon, the engagement thereof with the bevel gear 17 will cause the member 16 to rotate and to be moved with respect to its associated guide rod. Since the member 16 is carried by the slide 10, the rotational movement thereof will cause a reciprocating movement of the slide with respect to the guide rods so that the slide may be adjusted with respect to the bed for the die setting operation to insure the proper pressure between the upper and lower dies.

Each of the guide rods 6 and 7 is provided with a plurality of guide members or bearings which are stationary on a suitable part of the frame so that the rods may be guided properly in their reciprocating movement. One such guide member or bearing for each rod is indicated generally at 20 and is located in the cross member or crown 3 of the press. Each bearing includes preferably an extended tubular portion 21 having therein a bushing 22 in sliding contact with the rod. A cap 23 is positioned over the upper end of each rod so as to prevent dirt, dust and the like from entering the bearing at the upper side thereof.

Another guide member or bearing 24 is fixed to the frame below the slide for each of the guide rods. This bearing member includes an elongated tubular portion 25 within which a bushing 26 is in sliding contact with the lower portion of each guide rod.

It is thus evident that the guide span between the upper guide bearings 20 and lower guide bearings 24 is much greater than that which has been possible heretofore when cooperating gibbs were provided on the slide and frame.

The slide together with its guide rods is caused to reciprocate by customary drive means common to presses of this character. Thus, the drive means disclosed herein are located in the bottom of the press and include an eccentric strap 27 at each side of the press pivotally connected at its upper end by a pin 28 to the crosshead 5. The lower end of eccentric strap 27 has a portion 29 surrounding an eccentric member 30 on a shaft 31. Also mounted on the shaft 31 is a driving gear 32 in mesh with a pinion 33 on the shaft 34 which also has a gear 35 thereon driven by a pinion 36. This drive pinion 36 is mounted on the shaft 37 of a flywheel 38 forming a part of a clutch 39 and brake 40. A suitable motor 41 provides power to rotate shaft 37 by means of belts 42, whereupon rotation of shaft 31 will reciprocate the eccentric strap 27 and crosshead 5 connected thereto. Reciprocation of the crosshead at each side of the machine will

carry with it the four guide rods and the slide mounted thereon.

It will thus be observed that the gibbs heretofore used for many years have been completely eliminated and the reciprocating movement of the slide is guided entirely by the guide rods on which the slide is mounted in cooperation with the guide bearings mounted on the frame. The usual and customary counterbalancing means may be positioned in the crown of the press as indicated generally at 43 and comprises a cylinder 44 mounted on the crown, a piston 45 having a piston rod 46 connected thereto and mounted on the slide as at 47. Thus, reciprocation of the slide will cause the piston 45 to reciprocate within the cylinder 44 in the usual manner.

The application of the invention herein to a double action press is illustrated in Figs. 5, 6 and 7 wherein the press frame may be of the usual and conventional construction including uprights 48 at each end thereof and the crossbeam or crown 49 at the top. The double action press embodying the invention has been illustrated as being of the conventional bottom drive construction although it will be understood that a top drive can be utilized if desired.

The outer or clamp slide is indicated by the numeral 50 and is mounted on or suspended from an upper crosshead structure 51. The outer slide 50 is mounted on the upper crosshead 51 by means of a plurality of threaded rods 52 secured to the crosshead 51 and extending downwardly therefrom to threadedly engage upper and lower collars 53 and 54. There may be four such assemblies, one at each corner of the outer slide 50 to enable the outer slide 50 to be adjusted by hand with respect to the upper crosshead 51.

The upper crosshead carrying the outer slide is mounted on a plurality of guide rods 55 for reciprocation therewith. In the illustrated embodiment there are four such guide rods 55, one at each corner of the crosshead 51. The upper crosshead is also adjustably mounted on the guide rods 55 by means of a power operated adjusting device similar to that described above with respect to the single action press. In the present instance a worm gear 56 having an internally threaded sleeve 57 is secured or mounted upon the crosshead 51 by means of an outer sleeve 58 which permits sleeve 57 and worm gear 56 to rotate. The sleeve 57 engages a threaded section 59 on the guide rod 55, whereupon rotation of the worm wheel 56 will cause the associated part of the crosshead to be raised or lowered with respect to the guide rod. Power may be supplied by any suitable means for accomplishing this purpose, such as by a shaft 60 on which there is a worm 61 in mesh with the worm gear 56. Since there are four such assemblies, there will be a common drive means which may rotate all four worm gears simultaneously, thereby to raise and lower the upper crosshead 51 and the outer slide 50 connected thereto for adjustment with respect to the bed of the press.

Each guide rod 55 extends throughout the height of the press and is guided for reciprocating movement in an upper guide bearing 62 in the crown of the press, an intermediate guide bearing 63 and a lower guide bearing 64. At each side of the press the front and rear guide rods 55 are suitably secured at their lower ends to a crosshead 65. As will be seen hereinafter, suitable drive means are provided to reciprocate the crosshead 65 which will thereupon carry with it the guide rods 55 as well as the upper crosshead 51 and outer slide 50.

Again, the customary form of counterbalancing means may be provided for the outer slide consisting essentially of a plurality of rods 66 extending upwardly from the slide on each of which is mounted a piston 67 adapted to reciprocate within a cylinder 68 in the crown of the press during the reciprocating movement of the slide.

The inner slide 69 is mounted for reciprocating movement within the outer slide except that in the present

construction the mounting of this inner slide is independent of the outer slide so that adjustment of one will not affect the alignment of the other. The inner slide 69 is mounted on an upper crosshead 70 which has a plurality of threaded rods 71 extending downwardly therefrom. A power driven adjusting mechanism is provided for the inner slide 69 similar to that described above with respect to the upper crosshead of the outer slide. In this connection a worm gear 72 having an internally threaded sleeve member 73 is associated with each threaded rod 71. The gear 72 and its sleeve 73 are free to rotate about the rod 71 but are maintained in contact with the upper surface of the inner slide 69 by means of a retaining collar 74. Thus, rotation of the gear 72 associated with each rod 71 will cause the inner slide 69 to be raised and lowered with respect to the upper crosshead 70 on which it is mounted.

The crosshead 70 is mounted upon a plurality of guide rods 75 and in the embodiment shown there is one such guide rod 75 at each corner of the crosshead 70. A threaded portion 76 on each guide rod 75 is received within the crosshead 70 which is secured in place thereon by means of the upper and lower collars 77 and 78.

Each guide rod 75 is guided in its reciprocating movements by a plurality of guide bearings secured or fixed on suitable parts of the main frame. Each guide rod has an upper guide bearing 79 in the crown of the press, an intermediate guide bearing 80 below the crosshead 70, and a lower guide bearing 81. To counterbalance the inner slide, the customary counterbalancing means may be provided consisting of a plurality of upwardly extending rods 82 on each of which there is mounted a piston 83 adapted to reciprocate within a cylinder 84 in the crown of the press.

A lower crosshead 85 receives and is connected to the front and rear guide rods 75 at each side of the press. Suitable and well-known drive means is caused to reciprocate the crosshead 85 in timed relation with the reciprocation of the crosshead 65 for the outer slide so that both the outer and inner slides as well as the guide rods 55 and 75, respectively, upon which they are mounted will also reciprocate in their respective guide bearings.

The drive means for reciprocating the slides may include any well-known drive arrangements heretofore used for presses of this character. It is sufficient for present purposes to point out merely the salient features of the drive means which includes a drive shaft 86 at each side of the machine which has an eccentric 87 mounted adjacent the outer end thereof. This eccentric is connected to a crosshead 88 so that rotation of shaft 86 will cause the crosshead 88 at each side of the machine to reciprocate. A linkage arrangement including links 89 and 90 connects the crosshead 88 with uprights 91 extending upwardly from the lower crosshead 65 associated with the outer slide. A suitable power source 92 drives a chain of gears 93 to rotate each shaft 86, whereupon the crosshead 88 will reciprocate and will in turn reciprocate the crosshead 65. The linkage arrangement is provided for the purpose of causing a dwell in the outer slide in its lowermost position during the drawing operation performed by the inner slide.

Another eccentric 94 adjacent the inner end of shaft 86 has an eccentric strap 95 connected by means of a pin 96 to the lower crosshead 85 of the inner slide assembly. Rotation of shaft 86 therefore will also cause the crosshead 85, guide rods 75 and the inner slide mounted thereon to reciprocate in properly timed relation with the reciprocating movement of the outer slide.

Two of the main advantages obtained in the use of the present invention in connection with a double action press will immediately become apparent when it is noted that the customary gibs, not only between the outer slide and the frame but also between the inner and outer slides, are completely eliminated. The elimination of these gibs permits a greater guide span between the upper and lower

guide bearings of each of the guide rods than has been possible heretofore by the use of gibs. Furthermore, since the inner slide was formerly guided by gibs on the outer slide, it is apparent that an adjustment of the outer slide to bring it into alignment would thereupon move the inner slide out of alignment and vice versa.

These disadvantages are completely overcome in the present invention because both the inner and outer slides are guided independently of the other so that an adjustment of one slide for proper alignment will have no effect upon the alignment of the other slide.

Figs. 8, 9 and 10 illustrate the application of the present invention to a triple action press. In the particular press shown there is an outer clamp slide and an inner draw slide above the bed and arranged in a manner similar to that just described with respect to the double action press. In addition, however, a third action slide is reciprocally mounted below the bed for performing a second draw. The main difference between the double and triple action press as far as the present invention is concerned is the mounting and location of the outer and inner slides and the modification of the drive means to provide a dwell in the upper draw slide at the bottom of its stroke.

In these latter figures of the drawings the press is composed of the spaced uprights 97 at each side of the press connected at their upper ends by a crossbeam or crown member 98. The outer or clamp slide is shown in Fig. 9 and is indicated by the numeral 99. This outer slide is mounted upon an upper crosshead 100 by means of threaded rods 101 extending downwardly therefrom and which are received by suitable openings in the slide 99. Upper and lower internally threaded collars 102 and 103 support the slide 99 for movement with the upper crosshead 100 and also enable the slide to be adjusted with respect thereto.

The upper crosshead 100 is mounted upon a plurality of guide rods 104 in a manner similar to that described above with respect to the double action press. There is a guide rod 104 at each corner of the crosshead 100 each of which has a threaded portion 105 with which is associated a worm gear 106 having an internally threaded portion 107 engaging the threads 105. The gear arrangement 106 and 107 is mounted for rotation with respect to the guide rod 104 and is mounted upon the crosshead 100 by means of a retaining collar 108.

The guide rods 104 are mounted in suitable guide bearings for reciprocation therein. An upper guide bearing 109 is located in the crown and a lower guide bearing 110 is mounted upon the main frame. Each rod then extends downwardly through and is guided by the bed 111 and the front and rear guide rods at each side of the press are mounted in a lower crosshead 112. This crosshead 112 is caused to reciprocate by a suitable drive mechanism whereupon the upper crosshead 100 and outer slide 99 mounted thereon will also be caused to reciprocate.

Suitable counterbalancing means are also provided in the form of cylinders 113 mounted in the press crown within which pistons 114 may reciprocate. The pistons 114 have piston rods 115 connected thereto and with the slide 99.

The inner draw slide above the bed 111 is indicated at 116 in Fig. 10 and is mounted upon an upper crosshead 117 through the medium of the downwardly extending threaded rods 118. The inner slide 116 has associated therewith a power driven adjusting mechanism which includes the customary worm gear 119 and internally threaded portion 120 and the retaining collar 121. Rotation of the gear 119 will thereupon cause the slide 116 to move with respect to the crosshead 117 and to be adjusted for proper alignment.

The crosshead 117 is mounted upon a plurality of guide rods 122 one at each corner thereof. Each guide rod 122 has a threaded portion 123 thereon to threadedly

receive the upper and lower retaining collars 124 and 125. Thus, the upper crosshead 117 is adjustably mounted upon the reciprocating guide rods 122.

The guide rods 122 for the inner slide are also mounted in a plurality of vertically spaced guide bearings such as the upper guide bearing 126 in the press crown, the intermediate guide bearing 127 and the lower guide bearing 128 in the bed 111. A crosshead 129 is located at each side of the press and is mounted upon the front and rear guide rods 122. Suitable drive means are connected to the crossheads 129 to reciprocate them for in turn causing a like reciprocation of the upper crosshead 117 and the draw slide 116 mounted thereon.

The lower or third action slide 130 is mounted below the bed upon a plurality of arms 131 eccentrically mounted upon crank portions 132 of a drive shaft 133. A main gear 134 for the lower slide is mounted upon each end of shaft 133 and each is driven by a pinion 135 mounted at each end of a shaft 136. An intermediate gear 137 is also mounted upon shaft 136 and is driven from a suitable power source in timed relation with the movements of the other slides so that the lower slide 130 may be caused to reciprocate and perform a drawing operation during the dwell period of the upper draw slide 116.

This mechanism is conventional and it is illustrated herein primarily to show application of the novel guide means for the upper slides to a triple action press.

The press as shown in Figs. 8, 9 and 10 embodies a specific type of drive mechanism, the operation of which is described and claimed in my copending application Serial No. 289,143 filed May 21, 1952 now Patent No. 2,827,870 of March 25, 1958. For this reason only a brief description of the drive means will be presented here.

An outer slide crosshead 138 is provided at each side of the press which is connected by means of an arm 139 to an eccentric strap 140 surrounding an eccentric 141 on shaft 142. A main gear 143 is mounted upon shaft 142 at each side of the press so that rotation thereof will cause the crosshead 138 to reciprocate. A suitable linkage arrangement is connected at one end to the crosshead 138 and at the other end to a rock shaft 144 which has mounted thereon rocker members 145. The crosshead 112 is thus caused to reciprocate by the rock shaft 144 actuated by the gear 143 because of its connection with the rocker members 145. As mentioned above, reciprocation of the crosshead 112 at each side of the press carries with it the outer or blank holder slide 99 and the upper crosshead 100 on which it is mounted.

The inner slide is caused to operate by means of an arm 146 at each side of the press each of which is connected at its upper end by means of a pin 147 to the inner slide crosshead 129. The lower end of arm 146 is provided with an eccentric strap 148 which surrounds an eccentric 149 on a shaft 150. This latter shaft is caused to rotate by a gear 151 mounted thereon. Rotation of shaft 150 through the eccentric 149 thereon and

arm 146 will cause the crosshead 129 and the inner slide mounted on the guide rods 122 to reciprocate in properly timed relation with the movement of the other slides.

It will again be noted that the guide rods 104 and 122 are considerably longer than the gibs which have heretofore been used as guiding surfaces for the reciprocating movement of the slides. The fact that these guide rods may be guided in bearings spaced apart between the upper and lower ends thereof provides a greater guide span than has heretofore been possible. Finally, it will be observed that alignment of either slide may be effected without affecting the alignment of the other slide. This follows from the fact that with the present invention the inner slide is no longer guided in its reciprocation by the outer slide but rather is guided by independent means in the form of guide rods as above described.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

The invention is hereby claimed as follows:

1. A metal working press comprising, a frame, a plurality of upper and lower spaced and aligned bearing members fixed on said frame, a plurality of guide rods, each of said rods being slidably mounted in a pair of said aligned bearing members, a crosshead secured to said guide rods between said upper and lower bearing members, means to reciprocate said crosshead and guide rods, and a slide member mounted on said guide rods in spaced relation to said crosshead but also between the upper and lower bearing members therefor for movement with said rods, whereby the movement of said slide will be guided by said guide rods moving in said bearing members.
2. A metal working press as defined in claim 1 and which includes interengaging adjusting means on said slide and each of said guide rods for independently adjusting said slide with respect to said rods.
3. A metal working press as defined in claim 2 and in which said adjusting means includes retaining means mounted on said slide, and sleeves rotatably mounted in said retaining means and threadedly engaged with said rods between said upper and lower bearings.
